SEPARATOR FOR MEAT AND PRODUCE

Nola D. Levie, Los Angeles, Calif., assignor to Eko Products Company, Chicago, Ill., a corporation of Illinois

Application March 12, 1956, Serial No. 40,554

Term of patent 14 years

(Cl. D11—1)

Fig. 1.

Fig. 2.

Fig. 3.

Fig. 1 is fragmentary top plan view of a separator for meat and produce, showing my new design.

Fig. 2 is a fragmentary side elevational view thereof.

Fig. 3 is a perspective view thereof with a portion of the article broken away to shorten its longitudinal dimension for convenience of illustration.

I claim:

The ornamental design for a separator for meat and produce, as shown.
